Primary Examiner — Sandra L Morris(74) *Attorney, Agent, or Firm* — Paul Frank + Collins P.C.(57) **CLAIM**

The ornamental design for a plush toy, as shown.

DESCRIPTION

FIG. 1 is a perspective view illustrating the top and left side of an exemplary embodiment of the plush toy;

FIG. 2 is a top plan view of the plush toy of FIG. 1;

FIG. 3 is a bottom plan view of the plush toy of FIG. 1;

FIG. 4 is a right side elevation view of the plush toy of FIG. 1;

FIG. 5 is a left side elevation view of the plush toy of FIG. 1;

FIG. 6 is a front elevation view of the plush toy of FIG. 1; and,

FIG. 7 is a back elevation view of the plush toy of FIG. 1. Where applicable, shading is used for illustrative purposes only, and forms no part of the claimed design.
